The ornamental design for a bench, as shown and described.

DESCRIPTION

FIG. 1 is a top perspective view of a bench, showing my new design.

FIG. 2 is a front elevational view thereof.

FIG. 3 is a rear elevational view thereof.

FIG. 4 is left-side elevational view thereof.

FIG. 5 is a right-side elevational view thereof.

FIG. 6 is a top plan view thereof; and,

FIG. 7 is a bottom plan view thereof.

The broken lines showing legs, fasteners, and electrical ports are for the purpose of illustrating unclaimed subject matter.
